(57) **CLAIM**

The ornamental design for a stylus, as shown and described.

DESCRIPTION

FIG. 1 is a bottom, front perspective view of a first embodiment of a stylus in accordance with our new design;

FIG. 2 is a top plan view of the stylus shown in FIG. 1;

FIG. 3 is a bottom plan view of the stylus shown in FIG. 1; FIG. 4 is a left-side elevational view of the stylus shown in FIG. 1;

FIG. 5 is a right-side elevational view of the stylus shown in FIG. 1;

FIG. 6 is a rear elevational view of the stylus shown in FIG. 1; FIG. 7 is a front elevational view of the stylus shown in FIG. 1;

FIG. 8 is a bottom front perspective view of a second embodiment of a stylus in accordance with our new design;

FIG. 9 is a top, front perspective view of the stylus shown in FIG. 8;

FIG. 10 is a top plan view of the stylus shown in FIG. 8;

FIG. 11 is a bottom plan view of the stylus shown in FIG. 8; FIG. 12 is a left-side elevational view of the stylus shown in FIG. 8;

FIG. 13 is a right-side elevational view of the stylus shown in FIG. 8;

FIG. 14 is a rear elevational view of the stylus shown in FIG. 8; and,

FIG. 15 is a front elevational view of the stylus shown in FIG. 8.

The broken lines shown in the drawings represent portions of the stylus that form no part of the claimed design.
